SWITCH KNOB

Raymond N. Slate, Detroit, Mich., assignor to Moffats
Limited, Weston, Ontario, Canada, a corporation

Application December 3, 1953, Serial No. 27,907

Term of patent 14 years

(Cl. D26—13)

FIG. 1.

FIG. 2.

To all whom it may concern:

Be it known that I, Raymond N. Slate, a citizen of the United States, residing at the city of Detroit, county of Wayne, State of Michigan, have invented a new, original, and ornamental Design for a Switch Knob, of which the following is a specification, reference being had to the accompanying drawing, forming part thereof.

Fig. 1 is a perspective view of the switch knob, showing my new design, and

Fig. 2 is a perspective view thereof from a different angle.

I claim:

The ornamental design for a switch knob, as shown.
